APPARATUS FOR SPLICING THERMOPLASTIC
SYNTHETIC YARNS
Willie V. Williams, 701-717 S. Spencer St.,
Dalton, Ga.
Filed Feb. 12, 1963, Ser. No. 257,968
8 Claims. (Cl. 156—433)

This invention relates broadly to electrical heating apparatus and more particularly to apparatus for splicing 10 thermoplastic synthetic yarns and the like.

In the textile industry, a serious problem arises in a number of instances, for example in weaving and tufting operations when yarn ends must be spliced, as when changing from one yarn package to another. Knots are 15 undesirable and cause flaws in the work and knots cannot pass through the eyes of needles in tufting machines. It has been customary in the prior art to splice synthetic yarn ends with a latex adhesive composition and this is a tedious and uneconomical process and the resulting splice frequently shows up in the work as a dark spot or flaw resulting in rejects.

The object of this invention is to provide efficient and economical means to join or splice synthetic yarns including nylon and other well-known synthetics of the thermoplastic type. The splice is effected by the invention apparatus in a rapid and fool-proof manner, without the need for a skilled operator and without the need for cement, knotting, overlapping of ends or the like. The splice produced by the invention apparatus is clean and produces an exceedingly strong bond at the joined ends of the yarn with substantially no discoloration or interruption of the uniform yarn diameter or thickness adjacent the splice. Consequently, the use of this splice results in superior textile products which are free of the above-named imperfections caused by other types of splicing. The use of the invention apparatus also saves a great deal of time and labor and the apparatus is rugged and durable, easy to operate and relatively inexpensive to manufacture.

Other objects and advantages of the invention will be apparent during the course of the following description.

In the accompanying drawings forming a part of this application and in which like numerals are employed to designate like parts throughout the same,

FIGURE 1 is a perspective view of a synthetic yarn splicing apparatus according to the invention,

FIGURE 2 is a fragmentary side elevation of the apparatus viewed from the remote side of FIGURE 1 and showing in full and broken lines two extreme positions of a moving anvil and associated elements.

FIGURE 12 is an enlarged side elevation of a synthetic yarn splice formed by the invention apparatus.

In the drawings wherein for the purpose of illustration is shown a preferred embodiment of the invention, the numeral 15 designates a support base for the apparatus adapted to rest upon a table or the like and having an upstanding support plate 16 rigidly secured thereto as at 17 near one end of the base 15 and offset somewhat from one side thereof. Clamp bracket means 18 for an electrically heated sealing iron 19 of generally conventional construction is secured rigidly to one side of the plate 16 for gripping and holding the cylindrical shank portion 20 of the sealing iron 19. The sealing iron has an insulated handle 21 projecting beyond one end of the base 15 and an electric cord 22 extends through this handle in a conventional manner to convey current to the heating coil means of the iron for producing the required heat. A manually adjustable heat thermostat control means 23 is provided upon the body portion of the sealing iron. The iron has a sole or heating sealing plate 24 which faces upwardly and is inclined both longitudinally and laterally on the invention apparatus as shown in the drawings. 25 The iron 19 per se is to a great extent a conventional electrical heat sealing iron of the type employed in the packaging industry to seal cellophane wrappers and the like. In the invention, the sealing plate 24 may be modified somewhat by grinding, as will be explained, to form a relatively stationary V-shaped splicing anvil for coaction with a novel moving anvil and yarn clamping means according to the invention. In other respects, the iron 19 is conventional, as stated.

An elongated laterally narrow inclined rigid guide bar 25 is adjustably rigidly secured as at 26 to one side of plate 16 near the top thereof and this guide bar extends above the heat sealing plate 24 in spaced relation thereto and in somewhat divergent relation therewith toward the forward end of the iron. Near its longitudinal center, 30 FIGURE 3, the guide bar 25 carries a rigid lateral extension 27, preferably welded thereto, and extending horizontally across the top of the iron 19 and spaced therefrom. An upstanding stop lug 28 for a purpose to be described is secured rigidly to the extension 27.

40 A rectangular slide or carrier 29 is arranged forwardly of the plate 16 and above the iron 19 and guide bar 25 and rests slidably upon the forward top inclined edge 30 of the latter. The slide 29 has a dependent lug or pin 31 on one side thereof having sliding guided engagement 45 with the adjacent vertical face of the guide bar 25. Rigid with the slide 29 or integral therewith is a carriage bar 32 extending forwardly and rearwardly of the slide 29 and longitudinally of the iron 19 and bar 25 and movable with the carriage 29. The rear end of carriage bar 32 is 50 pivotally secured at 33 to an L-shaped crank 34, in turn pivotally secured at 35 to the upstanding plate 16, near and above the clamp means 18. The crank 34 has a thumb operated extension 36, as shown, disposed above the handle 21 so that the apparatus may be conveniently operated 55 with one hand during the splicing of yarn ends. Near and forwardly of the pivot 33, carriage bar 32 has a lateral extension 37 connected with the upper end of a retractile coil spring 38, the lower end of which is connected with an upstanding post 39 rigid with the base 15. The spring 38 serves constantly to hold the slide 29, bar 32 and associated elements downwardly and forwardly with respect to guide bar 25 and iron 19. Likewise, the spring 38 biases the thumb operated crank or lever 34 into a forwardmost position shown for example in FIGURE 1. In such position, the carriage bar 32 rests upon the lateral extension 27 of guide bar 25.

On the forward end of the carriage bar 32 and rigid

therewith is a movable anvil 40 having a yarn receiving slot 41 opening through its top and bottom faces and through its rear edge and offset from one side of the bar 32. This anvil 40 constitutes a very important element of the invention. The anvil 40 is provided in its bottom face with a forwardly tapering groove 42, FIGURES 7 and 8, which is also substantially V-shaped in cross section, FIGURES 9 through 11, and increases gradually in width and in depth from the front edge of anvil 40 to and through the back edge or rear edge thereof. The rear wider portion of this tapering groove 42 in the bottom face of the movable anvil falls directly within the confines of the slot 41 and intersects the same toward the rear of the movable anvil 40 as shown clearly in the drawings. The slot 41 forms a clamping shoulder 43 for yarn on the anvil 40 near the longitudinal center thereof.

A coacting depending yarn clamping dog 44 movable into and out of the slot 41 and toward and away from the shoulder 43 is carried by a clamp slide 45, having sliding engagement within a passage 46 formed through the carrier 29. A forward longitudinal extension 47 of slide 45 slidably engages the top of anvil 40 at one side of slot 41. One longitudinal edge 48 of slide 45 also slidably engages carriage bar 32. Slide 45 is equipped at its rear end with a cross pin 49 engaging back of stop element 28 to positively limit the forward movement of slide 45 with carriage bar 32 and associated elements. A retractile spring 50 of much lighter tension than spring 38 has one end secured at 51 to slide 45 and its other end is secured at 52 to slide or carrier 29. The spring 50 constantly biases slide 45 forwardly toward movable anvil 40 and these two elements may move in unison and they may also have relative movement during the operation of the apparatus, as will be further explained.

The operation of the apparatus for splicing monofilament nylon yarn or any like synthetic yarn is quite simple and is the following.

The electric cord 22 is plugged in to any convenient source of current and after a few moments the sealing plate 24 of the iron 19 will achieve the degree of heat under control of thermostat 23 necessary to effect the splice with the particular thermoplastic synthetic yarn such as a nylon. The degree of heat can be regulated, as stated.

The operator now merely introduces the two sections of yarn to be spliced into the slot 41 as depicted in the drawings and he may grasp lightly those ends of the yarns which hang below the anvil 40, FIGURE 1. His other hand is free to grasp the handle 21 and operate crank 34 with the thumb at 36.

The thumb element 36 is depressed and this immediately begins to retract carriage bar 32, slide 29 and movable anvil 40 as a unit toward the heating iron and the clamping dog 44. The spring 50 urges clamp slide 45 forwardly and prevents retraction thereof with the anvil 40 and in effect causes relative movement of the anvil 40 and clamping dog 44 toward each other as depicted in the drawings when the thumb extension 36 is initially depressed. Prior to full retraction of the anvil 40, the clamping dog 44, FIGURE 8, will grip the two ends of yarn in side-by-side relation within the slot 41 of the movable anvil and against the clamping shoulder 43 of the anvil. The two yarns are indicated at Y in the drawings. As soon as the yarn gripping or clamping action is effected, further depression of the thumb extension 36 will cause both the anvil 40 and clamping dog 44 to be further retracted in unison toward the heating iron along with the gripped yarn, see FIGURE 5. During this final retraction of the movable anvil 40 and associated elements, the lower face of the movable anvil and the groove 42 is caused to ride slidably onto the uppermost leading approximately square corner 53 of heating iron sealing plate 24, which corner 53 interfits with the tapering V-shaped groove 42 and forms the stationary anvil of the splicing apparatus. The stationary anvil 53 may be

ground or otherwise accurately shaped at the forward portion of sealing plate 24 to provide the proper configuration for mating sliding engagement within the groove 42 of the movable anvil. Both the groove and the corner or stationary anvil 53 are free of burrs and other imperfections or rough spots and the parts interfit and slide smoothly during the operation of the apparatus. As the movable anvil 40 rides up onto the stationary anvil 53, the spring 38 furnishes the required contact pressure between the two anvils.

During this action, the dependent ends of the yarn sections Y below the movable anvil 40 and clamping dog 44, FIGURES 5 and 6, are brought to bear upon the frontal edge and corner 54 of the stationary anvil 53 and the dependent yarn sections immediately melt and fuse and are severed or parted from the yarn portions which remain clamped within the slot H 1 and within the downwardly opening groove 42. Subsequent to this severing of the yarn ends, FIGURES 5 and 6, the entire carrier bar 32 is reciprocated several times by means of the thumb operated crank and while the clamped severed ends of yarn with the movable anvil 40 are riding on top of the stationary anvil 53, FIGURE 6. This action permanently fuses the clamped severed ends and forms a clean splice between the severed ends as depicted at S in FIGURE 12. The crank 34 may then be released abruptly by the operator and the parts will return automatically to their relative positions shown in FIGURE 1 and in most cases the firmly spliced yarn ends will actually spring out of the apparatus and the apparatus is cleared for further use for making additional splices in the identical manner. The splice S thus formed in exceedingly strong and appears to the naked eye as an almost perfect butt joint with substantially no discoloration of the adjacent yarn ends and no bulging or knotting or other obstruction or enlargement of the regular yarn diameter to show up as an imperfection in textile goods.

By way of summation, the apparatus when operated in the above manner first receives the two ends of yarn to be spliced, then securely grips the two ends and holds them while they are severed against the leading end and corner of the stationary anvil and finally fuses, welds and cleans the clamped ends to complete the splice by the application of heat and pressure and the unique rubbing action between the movable and stationary anvils where the V-shaped groove in the former receives the corner of the latter and subjects the clamped cut yarn ends to a final fusing and burnishing treatment.

The most important elements of the invention apparatus 50 reside in the movable anvil 40 with the slot 41 and groove 42, the coacting clamping dog 44 which may retract with the movable anvil after gripping the yarn and the coacting generally square cornered heated stationary anvil 53, as shown and described.

It is to be understood that the form of the invention heretofore shown and described is to be taken as a preferred example of the same, and that various changes in the shape, size and arrangement of parts may be restored to, without departing from the spirit of the invention or the scope of the subjoined claims.

Having thus described my invention, I claim:

1. Apparatus for use in splicing thermoplastic synthetic yarn comprising in combination a heating iron having an approximately square corner portion serving as a stationary heating anvil, a coacting movable anvil having a slot to receive yarn ends and a downwardly opening substantially V-shaped groove adjacent the slot, means to clamp said yarn ends within the slot of the movable anvil, means to move the movable anvil toward the stationary anvil with the clamped yarn ends so that the latter are fused and severed and permanently spliced by interfitting rubbing action of the stationary anvil within the groove of the movable anvil adjacent said yarn ends.

2. In an electrically heated synthetic yarn splicing apparatus, an electrically heated iron having a corner por-

tion forming a relatively stationary heated anvil, a slide structure, means to reciprocate the slide structure relative to said stationary anvil, a movable anvil and yarn clamping means on the slide structure and bodily movable therewith toward and away from the stationary anvil, the movable anvil having a through slot to receive yarn ends for clamping therein by said clamping means and also having a tapering groove in one face thereof adjacent said slot to slidably engage said corner portion forming the stationary anvil, and resilient means connected with the slide structure for urging it and the movable anvil into rubbing engagement with the stationary anvil.

3. Synthetic yarn splicing apparatus comprising a support means adapted to rest upon a table, a heating iron mounted upon the support means and having a generally square cornered portion forming a stationary heating anvil, a slide structure on the supporting means including a part forming a movable anvil, said movable anvil having a slot to receive yarn ends and a tapering generally V-shaped groove in its bottom face to ride slidably onto the stationary anvil for creating a rubbing force between said anvils, manually operable lever means connected with the support means and slide structure to reciprocate the latter and the movable anvil relative to the stationary anvil, yarn gripping means on the slide structure and movable therewith and also movable relative thereto for clamping yarn ends within said slot in side-by-side relation, and spring means connected with the slide structure to bias it forwardly relative to the stationary anvil and to also bias the movable anvil downwardly toward rubbing engagement with the stationary anvil.

4. The invention as defined by claim 3, and wherein said lever means is an L-shaped thumb operated crank lever pivoted to the support means and also pivoted to said slide structure, and a gripping handle on said support means in opposition to said lever.

means in opposition to said force.

5. Apparatus for use in splicing thermoplastic yarn comprising an electrically heated relatively stationary anvil having an approximately square cornered portion, a coating movable anvil having a yarn receiving slot and

an adjacent generally V-shaped groove for interfitting sliding engagement upon said corner portion, movable clamp means to engage yarn within said slot, and linkage means to reciprocate the movable anvil and said clamping means relative to the stationary anvil.

6. Synthetic yarn splicing apparatus comprising a relatively stationary anvil adapted to be heated, means to support said anvil, a movable anvil for interfitting rubbing engagement with the stationary anvil and having an opening to receive yarn ends, relatively movable clamp means on the movable anvil to grip the yarn ends within said opening, and manually operable means on the support means and connected with the movable anvil and clamp means to reciprocate the same relative to the stationary anvil.

7. The invention as defined by claim 6, and spring means connected with the movable anvil to resiliently bias the same toward rubbing contact with the stationary anvil.

0 8. Apparatus for splicing synthetic yarn comprising a tapering first anvil element, a coacting interfitting recessed second anvil element for rubbing action against the first anvil element, means to heat one of said anvil elements, means to cause relative reciprocation between said anvil elements while they are in interfitting rubbing relation, one of said anvil elements having opening means to receive yarn ends to be spliced, and resilient means to impart the required rubbing pressure at the areas of contact between said anvil elements.
